UNITED STATES PATENT OFFICE.

JÓZEFH PITRUS, OF CHICOPEE FALLS, MASSACHUSETTS.

STEEL-CUTTING MACHINE.

1,425,894.

Specification of Letters Patent. Patented Aug. 15, 1922.

Application filed March 17, 1921. Serial No. 453,057.

To all whom it may concern:

Be it known that I, JÓZEFH PITRUS, a citizen of Poland, residing at Chicopee Falls, county of Hampden, and State of Massachusetts, have invented certain new and useful Improvements in Steel-Cutting Machines, of which the following is a specification.

This invention relates to improvements in steel cutting devices, particularly adapted for cutting at one time a steel plate, bar, rail or the like into a plurality of parts of equal lengths.

It is the principal object of the invention to provide a device of this character which is adjustable for the cutting of steel or like articles of different widths.

Another object of the invention is the provision of a machine of this type which is easily operated by motor or other power, and which is simple and inexpensive, however reliable, durable and efficient.

Other objects and advantages of my invention will become more fully apparent as the description thereof proceeds by the inspection of the accompanying drawings, forming a material part of this disclosure, and in which:—

Figure 1 shows a machine constructed according to the present invention in side elevation.

Figure 2 is a top plan view of the same,

Figure 3 is a view partly in section along line 3—3 of Figure 1.

Figure 4 is a similar view in section taken along line 4—4 of Figure 2.

Figure 5 is a perspective detail view of a reciprocating saw guide.

A table 10 carries projections 9 between which a shaft 11 is journaled for a disc 12, and for the pulley or belt wheel 13, laterally disposed to said disc, over which a belt 14 is guided which is driven by a pulley 15 on a shaft 16 of a motor or other driving machinery.

To a projection of the bottom bar 17 of the table 10, a link 18 is pivotally secured at its lower end, the upper end of which carries a head 19, adapted to slide back and forth upon rods 20 supported in the table 10 and a leg 21 of the same.

The upper end of the link 18 is slotted as at 22, and a pin 23 of the head is adapted to execute a limited vertical movement in said slot.

A link 24 is pivotally secured with one

end to the disc 12 and with its other end to the link 18.

To the head 19, one arm of a bracket 25 is pivotally secured at one end, the other arm of which is secured by bolts 26 or the like to a guide head 27 for the locking bar 28 for the head blocks 29 of a plurality of hack saws 30 adapted to engage with their saw sockets 31, holes 32 of the blocks 29, while their opposite sockets at the end of the bows are engaged in the customary manner by wing nuts 33. The saws are reciprocated over a plate 34 provided with upright jaws 35 and sliding jaws 36 at the inner ends of screws 37 adapted to be operated by crank handles 38, while a rod 39 provided with left and right hand thread is adapted to adjust the distance between the two outer pairs of jaws and the intermediate pair of jaws upon the operation of its handle 40.

The cutter operates as follows:—

The steel bar or other article to be cut is placed between the jaws 35 and 36 and is clamped between these bars, after they have been properly adjusted by means of the handle 40 and rod 39, by the manipulation of the crank handles 38. When then the power is turned on to operate the pulley 15, the hack saws will be properly operated and during their reciprocating motion will cut the steel bar into a corresponding number of pieces of equal lengths.

It is clear that any number of saws may be arranged and that other changes may be made in the general arrangement and in the construction of the minor details of my invention without departing from the scope and spirit of the same.

What I claim as new, and desire to secure by Letters Patent of the United States is:—

1. In a steel cutter of the character described comprising a table, a plurality of saws mounted on said table to reciprocate transversely thereto, a head, adapted to be engaged by the head pieces of said saws, a headed bar engaged in said head for holding the heads of said saws in alignment on said head, a leg on said table, a horizontal rod supported by said leg, a head sliding on said rod, a disc on said table adapted to be rotated from a motor, link connections between said disc and said head for imparting to said head a horizontal reciprocatory movement, link connections between said head and the saw heads holding head for imparting to said saws a reciprocating mo-

tion, a plurality of movable and stationary jaws, a means for adjusting the movable jaws to accommodate a piece of steel to be cut by said saws, and means for clamping 5 the piece of steel in its adjusted position to be submitted to the action of said saws for cutting the same into a plurality of pieces of equal length.

2. In a steel cutter of the character described comprising a table, a plurality of 10 hack saws mounted for reciprocatory movement on said table, means for imparting to said saws their reciprocatory movement, a plate below said saws, stationary upright 15 jaws on said plate, a plurality of screws,

sliding jaws at the inner end of said screws, crank handles for operating said screws to clamp a piece of steel to be cut by said saws between said stationary and said movable jaws, a rod provided with left and right 20 hand thread, and a handle on said rod for operating the same to adjust the distance between the two outer pairs of jaws and the intermediate pair in accordance to the length of the pieces into which the steel piece is to 25 be cut.

In testimony whereof I have affixed my signature.

JÓZEFH PITRUS.
